Primary Examiner — Carla Jobe Wright*(74) Attorney, Agent, or Firm* — NSIP Law(57) **CLAIM**

I claim the ornamental design for a flip cover for mobile terminal, as shown and described.

DESCRIPTION

FIG. 1 is a front perspective view of a flip cover for mobile terminal showing my new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof;
 FIG. 7 is a bottom view thereof;
 FIG. 8 is a rear perspective view thereof;
 FIG. 9 is another front perspective view, in which the flip cover for mobile terminal is provided in an open position; and,
 FIG. 10 is another rear perspective view, in which the flip cover for mobile terminal is provided in an open position. The broken lines in the figures show portions of the flip cover for mobile terminal which form no part of the claimed design.
